TAPE MEASURE HOLDING SQUARE

Clarence Ose, R.R. 1, Echo, Minn. 56237

Filed June 17, 1974, Ser. No. 479,984

Term of patent 14 years

Int. Cl. D10—04

U.S. Cl. D10—65

FIG. 1 is a top plan view of a tape measure holding square showing my new design;

FIG. 2 is a front edge elevational view thereof;

FIG. 3 is a left side elevational view thereof;

FIG. 4 is a bottom plan view thereof;

FIG. 5 is a right side elevational view thereof; and FIG. 6 is a sectional elevational view thereof as taken from line 6—6 of FIG. 1.

I claim:

The ornamental design for a tape measure holding square, substantially as shown and described.
